UNITED STATES PATENT OFFICE

GEORGE FRANCIS RYAN AND ELMER HUNTON BURKE, OF LYNN, MASSACHUSETTS,
ASSIGNORS, BY MESNE ASSIGNMENTS, TO UNITED SHOE MACHINERY CORPORATION,
OF PATERSON, NEW JERSEY, A CORPORATION OF NEW JERSEY

PATTERN-COPYING MACHINE

Application filed October 29, 1926. Serial No. 145,087.

This invention relates to pattern copying machines and is disclosed as embodied in a lathe of the type set forth in U. S. Letters Patent No. 544,891, granted on the application of W. F. Gilman on August 20, 1895, for turning lasts.

A last lathe generally comprises a pendulum-like swing frame in which the model and work are carried and rotated opposite a model wheel carriage and a cutter carriage respectively, the carriages being arranged to traverse the model and work from one end to the other. The model rests against the model wheel and the block against the cutter; and the depth of cut is controlled by the relation between the model and model wheel.

As the model and block rotate in the swing frame, the frame swings back and forth, through two inches or so, during each rotation. The frame is about forty inches high and fifty inches long, and is shaped like a rectangular U. If made heavy enough to be really rigid, it jars the machine prejudicially as it swings, and if made light enough to avoid jar it is distorted to such an extent by the model reaction as to prevent good last cutting.

It has therefore been found necessary to adopt a compromise design and to run the machine more slowly than the cutter efficiency would warrant, about 15 to 30 revolutions per minute, and even then it has proved impracticable entirely to prevent jarring and distortion of the swing frame which has resulted in irregular reproduction from the model.

A principal object of the present invention is the avoidance of the above described difficulties, and we have found that the provision of a bracing member to support the model against the thrust of the model wheel is perfectly successful in this regard. Preferably this member is a contact or supporting member for the model on the opposite side from that engaged by the model wheel and is advantageously in the form of a wheel arranged to rotate against the model. In the disclosed construction the wheel is mounted on the model wheel carriage directly opposite the model wheel and travels along the model with it. Advantageously also the wheel is resil-

iently mounted to permit it to yield under the irregularities in the model contour, and it has been found additionally advantageous to provide it with a manually operated control to throw it into operative position and to release it.

These and other features of the invention comprising certain combinations and arrangements of parts will be apparent from the following description of a preferred embodiment of the invention shown in the drawings, in which

Fig. 1 is a front elevation of the machine,

Fig. 2 is a plan of the model and the members co-operating with it, and

Fig. 3 is an elevation of the parts shown in Fig. 2.

The illustrated machine disclosed is of an ordinary last lathe type having a main frame 10, a swing frame 12 pivoted at the top of the frame at 14, model dogs 16 and 18, and work dogs 20 and 22 in the swing frame by means of which the model 24 and work 26 can be continuously rotated, and a cutter carriage 28 and a model wheel carriage 30 arranged to slide along the frame. The cutter carriage carries the cutter 32 and the model wheel carriage carries the model wheel 34 and the width grading mechanism 36. The model wheel and the cutter carriages may be connected by a width grading mechanism 38 of any desired character. All of the above mentioned mechanism is well known in the art and needs no further description in view of the fact that it is fully disclosed in said Letters Patent.

The swing frame carrying the model and the block swings back and forth like a pendulum as the irregularities and contour of the model roll over the model wheel during the rotation of the model. This swinging movement of the swing frame regulates the depth of cut of the cutter 32 in the block 26 and thus reproduces the model as is well understood. It has proved impracticable to rotate the model and block at a speed of more than 30 revolutions per minute and even this speed is reached only on lasts or portions of lasts the contour of which approaches that of a cylinder. As the model wheel rolls over a high point in the model into a hollow the

machine experiences a jar and as the model wheel climbs out of this hollow it experiences another. Under the most favorable conditions this causes roughness in the work and 5 in general the jar is so severe as to distort the U-shaped swing frame and cause the cutter to cut too deep or too high on the block, thus destroying the accuracy of the reproduction. We have found that a steady- 10 ing member applied to the model opposite the model wheel will entirely obviate this difficulty.

In the disclosed construction this member is a wheel 40 having preferably a rubber 15 rim 42 of the hardness and resiliency of the rubber in a solid rubber ball. This wheel is mounted on a bell crank or lever 44 pivoted at 46 on the model wheel carriage. The lower arm of the lever is connected by a spring 20 48 to a treadle 50 mounted on the floor or the base of the machine having a ratchet mechanism 52 by means of which it may be locked down. This wheel 40 when in operative position engages the model opposite the 25 model wheel and is resiliently and tightly held against it by the spring 48 and this steadies the mechanism and permits the use of a considerably higher speed in rotation. The illustrated machine may be successfully 30 driven at speeds in excess of 50 revolutions per minute whereas the same machine with the wheel 40 removed to inoperative position and with the same model, when run at such speeds knocked the model completely out of 35 the machine.

The release of the treadle 52 permits the wheel 40 to be drawn back into inoperative position to enable the operator to remove or insert a model. The treadle is then lowered and is locked down, which forces the wheel 40 against the model, and the last is then cut in the ordinary manner. The mounting of the wheel on the model wheel carriage itself enables the opposite positions of the 45 wheel 40 and model wheel 34 to be continuously maintained but is unnecessary in order to secure some of the advantages of the invention.

Having described the invention, what we 50 claim as new and desire to secure by Letters Patent of the United States is:

1. In a pattern copying machine, an oscillating frame arranged to carry and rotate a model, a model wheel carriage, a model 55 wheel on the carriage arranged to contact with a model in the frame, a lever pivoted on the model wheel carriage, a rotary contact member on the lever arranged to roll on the model opposite the model wheel, and a manually operated member constructed and arranged to hold the contact member against the model, and to release it for removal to inoperative position.

2. In a pattern copying machine, an oscillating frame arranged to carry and rotate a

model, a model wheel carriage, a model wheel on the carriage arranged to contact with a model in the frame, a lever pivoted on the model wheel carriage, a rotary contact member on the lever arranged to roll on the model opposite the model wheel, a treadle, and a spring connecting the treadle with the lever to hold the contact member against the model. 70

3. In a pattern copying machine, an oscillating frame arranged to carry and rotate a model, a model wheel carriage, a model wheel on the carriage arranged to contact with a model in the frame, a lever pivoted on the model wheel carriage, a rotary contact member on the lever arranged to roll on the model opposite the model wheel, a treadle, a spring connecting the treadle with the lever to hold the contact member against the model, and means for locking the treadle in operative position. 75

In testimony whereof we have signed our names to this specification.

GEORGE FRANCIS RYAN.
ELMER HUNTON BURKE.
